B. M. KRELL ET AL

SPECIAL BOX PLAIT ATTACHMENT

Filed April 9, 1925

Patented Nov. 16, 1926.

1,607,131

UNITED STATES PATENT OFFICE.

BERNARD M. KRELL, OF NEW YORK, AND MEYER BRODY AND MICHAEL ZUCKERMAN, OF BROOKLYN, NEW YORK.

SPECIAL BOX-PLAIT ATTACHMENT.

Application filed April 9, 1925. Serial No. 21,770.

This invention relates to improvements in attachments for sewing the front seams in men's shirts, and also relates to a new construction of the front seam itself.

5 The object of the invention is to provide a new form of front seam for men's shirt whereby a less bulky front seam is obtained and which results in very substantial savings of material.

10 Another object of the invention is to provide a practical attachment for making the improved shirt front seam, said attachment being adapted to be attached to a sewing machine.

15 With these objects in view the invention is embodied in a new shirt front seam and attachment therefor arranged and constructed as hereinafter set forth and as illustrated in the accompanying drawing in which

20 Figure 1 is a view in cross section of a shirt front seam embodying the invention.

Figure 2 is a plan view of the attachment for forming the seam, parts being broken away.

25 Figure 3 is a side view of the attachment. Figure 4 is a longitudinal sectional view of the attachment.

Figure 5 is a transverse sectional view taken on line 5—5 of Figure 4.

30 Figure 6 is an end view of the attachment looking in the direction of arrow 6 in Figure 3.

Figure 7 is a bottom detail view of the lower forming members.

35 Figure 8 is a bottom detail view of the upper forming member.

The shirt front seam to which this invention relates is that part of a man's shirt in which the button holes are made. Both for 40 this reason and for the sake of appearance, the front seam is made of suitable width and of a double thickness of material reinforced by a strip of lining. The shirt front seam is usually one and one quarter inches 45 wide. If a double thickness of material is used, it takes twice as much in addition to the folds for properly forming the seams.

Heretofore it has been the custom to form the shirt front by sewing a strip of shirt material in front of the edge portion of the left part of the shirt in front.

This invention provides a construction in which the seam portion is formed in front, and a separate strip is sewn on the back 55 with a suitable lining interposed. In this

manner material is saved to the extent of the width of the front seam and the necessary folded portions and the back strip may be made of a cheaper grade of strip material so that it is not necessary to cut shirt material into strips, which is both expensive and wasteful.

60 Referring now to the drawing, Figure 1 illustrates in cross section the front seam or front portion of the left side of a man's shirt. In the drawing the numeral 10 denotes the front or outside and 11 is the back or inside which lies against the body. The numeral 12 denotes the left front shirt portion which covers the left side of the body 65 and extends to the edge 13.

Said shirt body portion 12 is adjacent the edge bent back upon itself at 14, thence bent again parallel to itself at 15. The material then forms the button hole portion 16 and 70 at the edge 13 the material is again bent upon itself.

75 Thus at 14—15 there is formed a double fold with three thicknesses of material and at 13 there is formed a single fold with two 80 thicknesses of material.

A lining 17 is laid within the folds against the portion 16. Back of the latter is placed an inside or back strip 18 being folded at both edges 19 and 20, and the parts are sewn 85 together by the two seams 21, 21.

90 The result is a shirt front seam having the same appearance as those now in use. But only one thickness of shirt fabric is used thus resulting in a material saving.

95 The attachment provided for automatically folding the materials as aforesaid comprises a lower folding member 22 and an upper folding member 23. The lower folding member is preferably formed of two members 24 and 25, which are soldered or otherwise joined to form a wider bottom channel 26 and narrow side channels 27, 27. The lower folding member has a wide entrance or mouth 28 and is tapered forward 100 to a flat spout 29. The side channels are tapered from the entrance towards the mouth, being first rounded as at 30 in Figure 5 and then tapering into narrow flat channels as at 31 in Figure 6.

105 The bottom channel 26 extends to both sides under the side channels 27 and tapers also horizontally as seen in Figure 4.

110 It will be understood that when a strip of material as the aforesaid back strip 18

is introduced or fed into the lower folding member through the entrance 28 it will be shaped gradually from the shape shown in a heavy black line in Figure 5 to pass out from the spout 29 with the folds 19 and 20 folded sharply flat against the portion 18 as in Figure 1.

The upper channel member 24 in the lower forming member 22 preferably extends beyond the spout 29 as shown to form a sharp guide tongue 32.

The upper folding member 23 has two channels, a lower lining channel 34 and an upper fabric channel 35. The lining channel 34 is relatively long and tapered from the entrance 36 to the flat spout at 37.

The fabric channel 35 is relatively short and has a flaring mouth or entrance 38.

The lining channel 34 is formed between the bottom 39 and middle member 40. The fabric channel is formed between the member 40 and top 41. The latter has a window 42. The middle member 40 extends beyond the spout at 37 to form a flaring guide tongue 43.

As shown in Figure 5, to the one side the top 41 is wrapped around the middle member and joined to the bottom to form a side channel 44 which extends in under the lining channel 34. The other side of the top is also wrapped or bent around the top as at 45 but is not joined to the bottom 39.

To the bottom 39 is joined a shelf 46, and the edge of the shelf and the edge of the top at 45 overlap forming a double side channel 47. Thus it will be seen that when the shirt material is introduced in the upper forming member as indicated by a heavy black line in Figure 5, the material will be formed with the edge fold at 13 in side channel 44, then lie on top of the middle member 40 and under the top 41. And on the other side the material will be folded within the portion 45 and double folded in the double channel 47 and the rest of the fabric will lie on the shelf 46. The lining which is a flat unfolded strip will be fed forward in the channel 34. The lining is not shown in Figure 5.

The window 42 is for the purpose of observing the fabric during its passage through the attachment, but it may be omitted as in Figure 6.

The three elements in the shirt front seam are fed forward into the attachment at the same time. The back strip 18 is fed in through the mouth 28, the lining is fed in through the mouth 36 and the front shirt material is fed in through the mouth 38.

As seen in the drawing, the folding mem-

bers are in vertical superposed relation and 60 converge in angular relation, the spouts 29 and 37 almost touching. The three said elements emerge at the spouts in proper relation to each other, the lining being contained within the folds 13 and 15 and all the folds 65 being very flat and sharp.

In this condition and position they are fed in under the sewing mechanism of a sewing machine indicated by the needles 50 in Figure 2, and as usual in this art, the sewing machine mechanism which includes a feed, draws the elements therethrough and 70 they are sewed together.

For purposes of support and adjustment the lower folding member has a stem 51 75 adjustably secured to a base 52 by screws 53. The upper folding member has a bracket 54 adjustably secured by screws 55 to a stem 56, which in turn is adjustably secured to the base 52 by screws 57. Thus lateral adjustment in two directions is assured. The base is suitably secured to the sewing machine table on top, not shown.

The several parts of the attachment are suitably joined by soldering, preferably, and 85 accomplish the object of the invention in automatically folding the fabric to form the improved shirt front seam.

We claim:

An attachment of the character described 90 comprising a lower folding element and an upper folding element, said lower folding element being adapted to fold the edges of a strip of fabric upon itself and comprising an upper member and a lower member joined to form a central flat channel and two rounded edge channels thereabove, the upper folding element being adapted to fold one edge of another piece of fabric back upon itself and for double folding an intermediate portion of said other piece of fabric as and for the purpose described, said upper folding element being bent to form a flat fabric channel merging into lower side channels at the edges thereof, a double folding channel formed in continuation of and below one of the said lower side channels, a member extending between said lower side channels to form a space for a piece of lining material below the flat fabric channel, all of the channels formed in the upper folding element being in substantial parallel relation, and means for supporting the said two folding elements with their axes converging and in the same vertical plane.
